[57] ABSTRACT

An adjustable lever arm extension for use on hand tools that employ an operating lever to apply force in operation of the tool. The extension is pivoted near the extremity of the operating lever, and has a grip that releases under predetermined force to permit the extension to pivot freely after that force has been reached. This limits the maximum amount of operating force applied by the tool.

LEVER OPERATED HAND TOOL IMPROVEMENT

BACKGROUND OF THE INVENTION

1. Field of the Invention

This invention relates to hand tools generally and more particularly concerns an improvement for lever operated hand tools.

2. Description of the Prior Art

While there are known arrangements for indicating torque in connection with hand tools having lever arm operation, they are not known to provide a release of actuation force when a predetermined maximum is reached. Nor is it known to provide an extension that is adjustable in lever arm length from the tool fulcrum with an arrangement for releasing the application of torque to the tool when a predetermined amount of force has been reached. It is the latter attributes which this invention specifically provide and which make practical a predetermined constant maximum application of torque, with respect to hand operated tools generally.

SUMMARY OF THE INVENTION

The invention relates to a combination that is applicable to a hand tool of the type having an operating lever for applying force in operation of the tool. The combination comprises lever extension means carried by said operating lever, and means for holding said extension means in operative relation with said operating lever. The latter means comprises means for releasing said holding means when a predetermined amount of force is applied to said lever.

Also briefly, the invention concerns a hand tool of the type having an operating lever for applying force in operation of the tool. It comprises in combination, a handle for use in applying said operating force, and means for effectively releasing said handle from operative relationship with said tool when a predetermined maximum force is applied.

Again briefly, the invention concerns a hand tool of the type having an operating lever for applying force in operation of the tool. The invention concerns a combination which comprises an auxiliary lever arm that has a permanent magnet adjustably mounted near the inner end of said auxiliary arm, and a handle located near the extremity of said auxiliary arm. The combination also comprises a support collar for holding said auxiliary lever arm slidably longitudinally therein and pivot means for attaching said collar to said operating lever near the extremity thereof. The combination also comprises means for adjustably securing said auxiliary lever arm in said support collar, to permit variable setting of the spacing of said permanent magnet from said pivot along said operating lever.

BRIEF DESCRIPTION OF THE DRAWINGS

The foregoing and other objects and benefits of the invention will be more fully set forth below in connection with the best mode contemplated by the inventor of carrying out the invention and in connection with which there are illustrations provided in the drawings, wherein:

FIG. 1 is an elevation of an assembly, illustrating the invention as applied to the operating lever arm of a banding tool that is shown in dashed lines; and

FIG. 2 is a fragmentary elevation showing the same assembly view as FIG. 1 but with the parts in operating position for application of torque to the operating lever of the tool.

DESCRIPTION OF THE PREFERRED EMBODIMENT

It is to be observed that the invention is applicable generally to any hand operated tool which is actuated by the application of torque, e.g., by means of an operating lever. While FIG. 1 of the drawings illustrates somewhat schematically a banding tool, it will be appreciated that many other hand operated tools might have this invention applied thereto.

With reference to the FIGS. 1 and 2 of the drawings, it will be noted that there is a hand operated tool 11 that is shown only in FIG. 1. Since it is not a material part of the invention, it is illustrated in dashed lines.

Thus, there is a tool 11 which might take other forms but is illustrated as a banding tool. It has an operating lever 12 which is actuated manually to apply torque in providing operating force for actuating the tool 11. The lever 12 is pivoted about a pivot point 15 (FIG. 1) on the tool 11, and such pivotal action applies a torque to cause operation of the tool.

In order to have predetermined and adjustable maximum force that may be applied to the lever 12, there is an auxiliary lever arm 16. This and its related elements are shown somewhat exaggerated in relative size viz-a-viz the tool 11 and its handle or lever 12. However, it will be understood that such is a matter of design and therefore is a matter that is within the purview of one skilled in the art.

The arm 16 is slidable longitudinally within a collar 17, which in its turn is pivotally mounted near the end of the lever 12 by means of a pivot pin 20. The pin 20 extends through both sides of a bifurcated portion of the collar 17, which portion straddles the lever arm 12. It will be noted that there is a set screw 21 in the top (as viewed in the drawings) of the collar 17. This acts of fix the slidable position of the auxiliary lever arm 16 relative to the collar 17.

At the outer extremity (relative to the tool 11) of the auxiliary arm 16 there is a spherical handle 22 for being gripped manually as force is applied to the tool. At the other end of the arm 16, i.e., the end which when pivoted will lie substantially parallel with the lever arm 12 (see FIG. 2) there is a bracket 26 that is integrally attached to the end of the arm 16. While the bracket 26 might take various forms, it may be constructed of an angle shaped body which stands with one half at right angles to the end of the arm 16 where it is attached thereto. The other half lies parallel to the arm 16 so as to form a support for a permanent magnet 27. Magnet 27 is mounted in a housing 28 in any feasible manner, e.g., by being pinned therein as indicated by a pin 29. The housing 28 is mounted pivotally near the extremity of the bracket 26, and this may be accomplished in any feasible manner such as that illustrated. There is provided a lug 32 which is integral with and extends from the top of the housing 28, and a pivot pin 33 extends through the free end of the bracket 26 and through the lug 32 so as to provide the desired pivotal support for the housing and the magnet contained therein.

In order to hold the pivotal support for the magnet in position to provide an even gripping action against the lever arm 12 of the tool, there is an adjustment screw 36. The screw 36 extends through a tapped hole in the upstanding portion of bracket 26 and rests against the side of the housing 28. There is a nut 37 which may be tightened against the bracket 26 so as to maintain a desired pivotal position of the housing 28.

OPERATION

It will be appreciated that the operation of this invention involves the ability to adjust the maximum amount of force that will be applied by a hand tool which employs a lever arm that is manually actuated. This entails the use of the pivotally attached auxiliary arm 16 which is mounted near the free end of the lever 12. The arm 16 may swing freely about its pivot 20 except when the magnet 27 is in contact with the lever 12. It will be appreciated that if the lever 12 is not constructed of a ferrous metal, there would be provided a strip (not shown) along the upper edge of the lever for having the magnet 27 make gripping contact therewith.

With reference to FIG. 2, it will be noted that this is the position the parts will take prior to the application of force in operation of the tool. Now, the maximum amount of force which may be applied to the tool depends upon the total amount of force, which includes the leverage from handle 22 to the tool operating pivot 15. However, this is only true so long as the magnet 27 remains in gripping contact with the lever 12. Consequently, whenever the amount of force being applied to the handle 22 exceeds that amount required to cause the magnet 27 to break free from the tool lever arm 12, the auxiliary arm 16 will pivot freely and application of force to the tool will cease. Thus, a predetermined maximum appli-

cation of torque is transmitted to the tool, and this may be adjusted for different desired forces by adjusting the position of arm 16 in its supporting collar 17. It will be appreciated that the force on the magnet 27 tending to break it out of contact with the lever 12, changes as the setting of the auxiliary arm 16 is changed.

As an example of the foregoing it will be noted that if the auxiliary arm 16 is set with the handle 22 close to the end of the lever arm 12, there will be greater force necessary to break the magnet 27 free and greater maximum force may be applied to the tool. The change (reduction) in the leverage of the tool input will have less effect than the change in the maximum force that can be applied before the magnet breaks free.

While the foregoing specific embodiment of the invention has been set forth in considerable detail in accordance with the applicable statutes, this is not to be taken as in any way limiting the invention but merely as being descriptive thereof.

I claim:

1. In a hand tool of the type having an operating lever for applying force in operation of the tool, the combination com-

- prising
 an auxiliary lever arm with
 a permanent magnet adjustably mounted near the inner
 end of said auxiliary arm, and
 a handle located near the outer extremity of said auxiliary
 arm,
 a support collar for holding said auxiliary lever arm slidably
 longitudinally therein,
 pivot means for attaching said collar to said operating lever
 near the free end thereof, and
 means for adjustably securing said auxiliary lever arm in
 said support collar to permit variable setting of the spacing
 of said permanent magnet from said pivot means
 along said operating lever.
- 10 2. The invention according to claim 1 wherein said operating lever is constructed of ferrous metal, and
 wherein said adjustable mounting for said permanent magnet is pivotal to permit even contact by the magnet with
 said operating lever.
